(57) **CLAIM**

The ornamental design for a 3D printer housing, as shown and described.

DESCRIPTION

FIG. 1 illustrates an elevated right-side perspective view of a 3D printer housing;

FIG. 2 illustrates an elevated left-side perspective view, thereof;

FIG. 3 illustrates a bottom left-side perspective view thereof;

FIG. 4 illustrates a bottom right-side perspective view thereof;

FIG. 5 illustrates a front view thereof;

FIG. 6 illustrates a posterior view thereof;

FIG. 7 illustrates a top view thereof;

FIG. 8 illustrates a bottom view thereof;

FIG. 9 illustrates a left-side view thereof;

FIG. 10 illustrates a right-side view thereof; and,

FIG. 11 illustrates an elevated right-side perspective view of the 3D printer housing with three cartridges for printing three-dimensional objects.

The broken lines shown represent unclaimed subject matter and form no part of the claimed design.

1 Claim, 11 Drawing Sheets
